UNITED STATES PATENT OFFICE.

JULIUS NUESKE, JR., OF NEW YORK, N. Y., ASSIGNOR TO L. MUNDET & SON, INC., OF BROOKLYN, NEW YORK, A CORPORATION OF NEW YORK.

MACHINE FOR MAKING CORK INSOLES.

Application filed September 4, 1925. Serial No. 54,391.

This invention relates to a machine for making fabric covered cork insoles, and to the manufacture of said insoles.

Heretofore, in the conventional fabric covered cork insole, the edges of the fabric covering have been pasted to the upper face of the cork sheet. This mode of fastening the parts together is comparatively expensive in time, material and effort, the pasting operation consuming a considerable amount of glue or paste and being of necessity performed entirely manually.

My invention contemplates the production of a machine for making an insole wherein the edges of the fabric covering are secured to the cork sheet solely by mechanical means whereby the parts are interlocked, the necessity for pasting or otherwise cementing the parts together being thereby completely eliminated.

The various objects of my invention will be clear from the description and from the drawings, in which,

Fig. 1 is a top plan view of my improved machine.

Fig. 2 is a vertical section of the same on the line 2--2 of Fig. 1.

Fig. 3 is a similar partial view of the same showing another position of the parts.

Fig. 4 is a vertical section on the line 4--4 of Fig. 1.

Fig. 5 is a bottom plan view of the locking plate.

Fig. 6 is a top plan view of my improved insole, partly completed, the thicknesses of the material and of the slit being greatly exaggerated for clearness, and

Fig. 7 is a vertical section of the same.

In the operation of my improved machine, the undersurface of the cork sheet 10 is completely covered with the fabric covering 11 which is made of material sufficiently wide to cover the entire peripheral edge 12 of the cork sheet 10 and to reach on to the upper surface 14 thereof in the usual manner.

The edge portion 13 of the covering 11 is forced and wedged at intervals preferably without puncturing the covering into the material of the cork sheet, and it is the structure whereby the cork sheet and the covering are wedged or interlocked together that forms one of the features of this invention. A cut or slit 16 of little width and of

a depth preferably insufficient to pass completely through the sheet 10 is made in said sheet in any suitable manner as by means of a chisel-edged tool as will be more fully described hereinafter. If a portion of the covering 11 is then forced into and preferably down to the bottom of said slit 16, the elasticity of the cork is sufficient to cause the walls 15 of said slit to spring toward each other in the tendency of the cork to close the slit, whereby the material 17 forced into said slit is firmly gripped and retained in the slit between the walls 15.

The covered cork sheet may then be finished by the attachment thereto, in the usual manner, of a covering sheet of oilcloth, not shown, as by means of suitable stitching well known in the art.

In the machine embodying my invention I provide a sole plate 20 having an opening 21 therein of the proper shape and size to conform to that of the insole, said opening or depression being substantially of the same depth as that of the cork sheet 10. Said plate is preferably mounted on a suitable anvil sheet as 22 of softer material, such as fiber secured on the bed 23 of the main frame 24 of the machine for the purpose of providing a comparatively soft anvil whereby the slitting teeth which may accidentally penetrate the cork sheet 10 would remain uninjured, as will be pointed out specifically hereinafter.

The operator first arranges the previously shaped cork sheet 10 on the larger shaped fabric covering 11 and properly positions said sheet and covering so that said covering projects substantially uniformly over the edge of said sheet. He then inserts both pieces into the depression 21 whereby the edges 25 of said covering are forced to stand up above the surface of the depression 21, the covering being properly tensioned about the under surface 9 of the cork sheet 10 simultaneously, as will be readily understood.

Means are provided for bending over the upstanding edges 25 on to the upper surface 14 of the sheet 10 before the pieces are secured together. Said means comprises the horizontally reciprocating end plates 26 for turning over the end portions 27 of the edges 25 and the side plates 28 arranged to reciprocate perpendicularly to the plates 26 for

turning over the remainder of the upstanding edges 25. Since both of said plates 26 are substantially identical in structure, a description of one will suffice for both.

5 Said plate 26 is secured as by means of the screws 27 to a slide 78 arranged to slide on the arm or extension 34 and provided with a slot 29 extending longitudinally thereof. Fixed in said slide 28 and extending across 10 said slot is disposed the pin 30. Said pin is arranged to operate in the cam slot 31 of the sliding cam 32, said cam reciprocating vertically in the slot 33 of the extension or arm 34 outstanding from the bed plate 23. 15 The four-armed vertically reciprocating frame 35 has one of its arms 36 secured to the lower end of the sliding cam 32 as by means of the bolts 37, whereby the said cam is vertically reciprocated on the reciprocation of said frame. An upright rod 38 secured to the center of said frame 35 is arranged for bodily movement vertically, and is designed to be lowered when it is desired to turn over the edges 25 of the fabric covering 11. Said rod is supported in a suitable bearing 39 in the main frame, a spring as 20 being interposed between said bearing and said frame and serving not only to take up undue pressure or excess motion which may be due to the movement of the rod 38 too far downwardly, but also to return the parts to their initial position.

For reciprocating the side plates 28 horizontally toward each other, each of said 25 plates is suitably secured to and underneath the plate frame 41 as by means of the screws 42. To the substantially horizontal central extension 43 on said plate frame is revolvably secured a suitable roller as 44 operating in the slot 45 of the bell-crank lever 46. An 30 arm 47 projecting from the bed plate 23 serves as a support for said bell-crank lever, which is pivoted thereto as at 48. The link 49 connects the end 50 of said lever to the arm 51 of the four-arm frame 35. For 35 guiding the side plate 28 in its peculiar reciprocatory movement a pair of similar links 52 and 53 are each pivoted at one end thereof to said frame, said links being pivoted at the lower ends thereof to the bed plate 23 as by means of screws 54 and 55 respectively.

It will be seen that on the depression of the rod 38, and the consequent downward movement of the frame 35, the cams 32 are 40 moved downwardly causing the end plates 26 to move inwardly toward each other and to fold over the ends 27 of the covering 11, while the links 49 are simultaneously depressed, rotating the bell-crank levers 46 about their pivots 48 and causing the side plates 28 to move inwardly toward each other, the movement of said plates being controlled by the links 52 and 53.

45 Said links cause said plates 28 first to rise slightly until said links assume their

upright position and then to move slightly downwardly to complete the folding operation whereby the upper edges of the upstanding edges 25 are properly thrown over and the successful operation of the folding mechanism is assured.

After the edges 25 have been folded down on the surface 14 of the cork sheet, the notching or slitting hammer is then operated. Said hammer comprises the main plate 56, supported horizontally at all times for movement about the pivot points 57 and 58 on the arm 59 extending from the main frame 24 of the machine. At the pivot points 57 and 58 are secured the links 60 and 61 respectively, the upper ends of which links are pivoted to said plate 56 at the points 62 and 63 respectively. To the underside of the plate 56 is secured the punch plate 64 wherein are set the chisel-edged pins 65, said pins being arranged at spaced intervals in such a manner that they contact with the folded edge 13 of the covering 11 between the peripheral edge thereof and the wall 12 thereof, in the lowermost position of said plate. A bumper as 66 preferably of rubber is secured to said plate 64 inside of said pins to take up the shock caused by the lowering of said hammer with undue force. A series of spaced slots as 67 are made in the folding plates 26 and 28 whereby the peripheral edges of said plates are cut up into a series of tongues 74. The pins 65 are arranged to register with and to pass through the slots 67 in the folding plates 26 and 28 whereby said pins may pass said folding plates into operative engagement with the folded edge 13 and the cork sheet 10, in the lowermost position of said hammer.

100 The chisel edges 75 on the pins 65 engage the folded edge 13 of the fabric covering after said edge has first been folded and held down on the surface 14 of the cork sheet 10 by the folding plates. When the hammer is brought down to its lowermost position, the sharp edges 75 form a slit 110 in the cork sheet and simultaneously stretch the fabric covering sufficiently to force part 115 thereof in between the walls 15 of the slits without tearing or forming holes in the covering. The bumper 66 is so designed that the edges 75 do not pass completely through the cork sheet, but should they do 120 so due to defects in said sheet or the use of undue force, the fiber anvil sheet 22 prevents injury to said edges.

125 The ends 76 of the plates 28 are preferably partly undercut as at 77 to allow the end plates 26 to pass thereunder (Fig. 4) so that the entire edge portions 25 of the covering 11 may be properly folded. I prefer to so design the mechanism for operating the folding plates 26 and 28, that the end plates 26 130 start to fold the ends 27 of the covering 11

just before the movement of the side plates 28 is begun. By this arrangement the ends 27 may be partly folded down out of the way so that the folding of the remainder of the 5 edge portions 25 of the fabric covering may be completed and a substantially flat folded surface produced. It will be understood that any folds in the material of the covering occurring during the operation are flattened 10 out on the operation of the side plates 28, particularly if the folding of the ends is begun before that of the remainder of the edge portions. Suitable means are provided for preventing side sway of the hammer plate 15 56. In the form illustrated said means comprises the shaft 68 supported in the bearings 69 and 70 of said hammer plate and carrying at the ends thereof the arms 71. At the end of each of said arms is provided the roller 20 72 adapted to engage the link 60, said roller being pressed into engagement with said link by means of the coiled springs 73 on the shaft 68, and serving to resist all movement of the hammer plate except bodily movement 25 thereof about the pivot points 57 and 58.

The operation of my improved machine is as follows:

The cork sheet with the fabric covering thereunder and projecting uniformly therefrom having been inserted into the opening 30 21 of the plate 20, and the edges 25 of the covering having thereby been upraised to some extent, the rod 38 is depressed, thereby lowering the four-arm frame 35, which in 35 turn lowers the cams 32 and the links 49. The pin 30, the slide 78 and end plate 26 are carried by said cam inwardly of the machine to fold the end portions 27 of the covering, and the link 49 rotates the bell- 40 crank lever 46 about its pivot 48 thereby moving the plate frame 41 and the side plate 28 carried thereby first upwardly and inwardly about the link pivots 54 and 55 and then downwardly and inwardly to complete 45 the folding. The hammer is then brought down with the necessary force whereby the covering is forced into the slits simultaneously formed in said cork sheet completing the assembly of the parts. The hammer is then 50 raised into its initial position against the stop 79 and the rod 38 released, whereby the spring 40 carries the parts back into initial position in readiness for the repetition 55 of the operation.

I do not wish to be understood as being limited to that specific embodiment of my improved machine shown and described, as I intend to claim the invention as broadly as may be permitted by the state of the prior 60 art.

I claim:

1. In a machine for making insoles, a plate having a cut-away portion shaped to fit an insole and adapted to receive a fabric 65 covering and a cork sheet, reciprocating

means for engaging and folding the entire edge of said covering on the top of said sheet at one time in a single reciprocation of said means, and means for locking said covering to said sheet. 70

2. In a machine for making insoles, means for receiving a sheet and a fabric covering therefor, means for folding the edges of said covering, and means for forcing parts of said edges at spaced intervals into the interior of said sheet. 75

3. In a machine for making insoles, means for receiving a flat sheet and a covering, and adapted to raise the projecting edges of said covering on the insertion of the sheet and the covering into said means, means for folding said edges down onto said sheet in a single movement, and means for simultaneously locking the peripheral edges of said covering to said sheet at points around the periphery thereof. 80

4. In a machine for making insoles, means for locking the covering of an insole to its body portion comprising pins for forcing an imperforate portion of said covering into the body portion of said insole. 90

5. In a machine for making covered insoles, a series of chisel-edged pins, and means for supporting said pins and for forcing said pins into an insole, whereby said pins carry parts of the covering for said insole into the body portion thereof, and allow said body portion to wedge said parts on the withdrawal of said pins. 95

6. In a machine for making insoles, means for folding a covering over the body portion of an insole comprising means for folding the projecting ends of said covering on to said body portion and means for folding the remainder of the projecting part of said covering on to said body portion, and means operating upon the material of said covering for forming spaced slits in said body portion and for forcing said folded covering into said slits. 100

7. In a machine for making insoles, means for folding the edges of a covering on to a cork sheet, and means for forcing said covering into said sheet and simultaneously making slits in said sheet at the points where said covering is forced thereinto. 115

8. In a machine of the character described, means for folding a covering on to a cork sheet, comprising a reciprocating folding plate having slots at the inner end thereof, and locking means arranged in alignment with, and adapted to pass through, said slots, for forcing said covering at spaced intervals in the interior of said sheet. 120

9. In a machine for making insoles, means for locking the edges of a covering on to a cork sheet comprising a plate, edged pins projecting from said plate and set at spaced intervals in a line parallel to the edge of the sheet, and a bumper having a peripheral 130

- edge substantially parallel to the line passing through the centers of said pins, and of less thickness than the height of said pins for limiting the depth to which said pins are permitted to pass into said cork sheet.
10. In a machine of the character described, means having a depression therein for receiving a sheet and a covering for the sheet, a folding plate having a slot therein, and means for reciprocating said plate in a plane above the receiving means for causing said plate to fold the covering comprising a slotted cam mounted for reciprocatory movement in the slot of said plate and a pin on said plate engaging the cam slot of said cam.
11. In a machine of the character described, means having a depression therein for receiving a sheet and a covering for the sheet, a folding plate, means for reciprocating said plate in a plane above the receiving means for causing said plate to fold the covering comprising a bell crank lever pivotally secured to said plate and means for oscillating said lever, a series of parallel links each pivoted at one end thereof to said machine for controlling the movement of said plate, and means for pivotally securing the other end of each of said links to said plate.
12. In a machine of the character described, means for holding the projecting end of an insole covering over the cork sheet therefor comprising a slotted plate, and a slotted reciprocating cam operatively connected to said plate, means for folding the projecting sides of said covering over said sheet comprising a slotted plate and means for reciprocating said plate, and means adapted to pass through the slots of said plates in the inward position of said plates for forcing parts of said covering into said sheet.
13. In a machine for making insoles, a reciprocatory frame, a slotted end folding plate, means operatively connecting said plate and said frame for reciprocating said plate on the movement of said frame, a slotted side folding plate, means operatively connecting said side folding plate to said frame, and edged pins adapted to pass through the slots of said plates after said plates have completed the folding movement and partway through said insole for making slits in said insole. 45
14. In a machine for making insoles, means for folding the covering of a sheet thereover and for maintaining said covering in folded position, and means for locking the entire peripheral edge of said covering to said sheet in a single movement. 50
15. In a machine for making insoles, a locking hammer comprising a plate, edged pins set at spaced intervals in and projecting from said plate, and a bumper projecting from said plate inside of, and of less thickness than, the height of said pins. 55
16. In a machine of the character described, means for folding the projecting end of an insole covering over a cork sheet therefor comprising a slotted plate, and a slotted reciprocating cam operatively connected to said plate, means for folding the projecting sides of said covering over said sheet comprising a slotted plate, and means for reciprocating said plate, and means adapted to pass through the slots of said plates in the inward position of said plates for forcing parts of said covering into said sheet, comprising a series of edged pins, means for supporting said pins, and means for controlling the movement of said pin supporting means. 70 75
